dril Company, Los Angeles, Calif., a corpora-
tion of California

Application August 24, 1936, Serial No. 97,632

17 Claims. (Cl. 166—14)

This invention has to do with oil well packing heads, used for the purpose of sealing around drill pipe or other work extending through the head into the well pipe, and particularly with improvements in packing heads of the type disclosed in Patent No. 2,038,140, issued April 21, 1936, on Packing head, and in our copending application, Ser. No. 50,482, filed November 19, 1935, on Packing head.

10 In the present type of packing head, a radially contractible packer is pressed into engagement with the work by a contractor, preferably in the form of a piston, that is movable vertically within the housing. Various aspects of the invention are conveniently applicable to packing heads of this type in which the packer contracting piston is actuated by fluid pressure, although it is to be understood that in certain of its broad aspects, the invention is not to be regarded as limited to packing heads in which the packer is piston actuated, or, where a packer actuating piston is used, to one operated by fluid pressure. Without going into detail at this point, it may be stated that the main objects of the invention are directed to improvements in the packer construction and mounting, adjustable stop control means for the packer contracting piston, and to various improvements in the construction, arrangement and control of packing heads in tandem arrangement, operating to maintain a fluid tight seal about the work as it is being lowered into or withdrawn from the well.

15 All these generally stated purposes of the invention, as well as various other features and objects, will be most readily understood and explained to best advantage without further preliminary discussion, from the following detailed description of the invention in one of its typical and preferred forms. Reference is had throughout the description to the accompanying drawings, in which:

10 Fig. 1 is a general view, in elevation, showing a typical embodiment of the invention comprising a pair of packing heads in tandem arrangement, certain of the connections therewith being shown diagrammatically;

15 Fig. 2 is a longitudinal sectional view of the upper packing head illustrated in Fig. 1, the main packer being shown in radially constricted position;

20 Fig. 2a is a fragmentary section as viewed on line 2a—2a of Fig. 3, but showing the packer compressed into engagement with the flat surfaces of the drive stem;

25 Fig. 3 shows the lower packing head in longitudinal section, with the packer in released posi-

tion. For purposes of describing certain aspects of the invention, as will later appear, the packing head in this view is shown to take a drive stem of polygonal cross section.

Figs. 4 and 5 are sectional views taken on lines 4—4 and 5—5, respectively, of Fig. 3;

Fig. 6 is a fragmentary enlargement of the check valve in the vent passage leading from the chamber above the main packer;

Fig. 7 and 8 are fragmentary enlarged views showing a portion of the indicator mechanism in changed positions;

Fig. 9 is a sectional view showing another form of packing head embodying the invention; and

Fig. 10 is a fragmentary enlarged view of the indicator piston in Fig. 9.

In the typical and illustrative form of the invention shown in Fig. 1, a pair of packing heads 10 and 11 are shown to be mounted in tandem arrangement above the well pipe or casing 12, the individual packing heads and their connections forming a general head assembly 13 adapted to maintain a fluid tight seal about the drill pipe or other work during drilling operations, or while the pipe is going into or out of the well, all in the manner later to be described in detail. Heads 10 and 11, while generally similar, have certain differences in construction and operation that adapt them to their particular functions in the operation of the head assembly 13. In describing the construction of the two packing heads, reference first will be made to their common structural features, using the same reference characters for corresponding parts, and then to the structural aspects in which the heads are differentiated.

The lower head 11 is attached to the well casing 12, and upper head 10 to a pipe 14 interconnecting the two heads, by couplings 15 having threaded box ends 15a receiving the threaded ends of the pipes. Each packing head comprises a tubular body or housing 16 having a lower reduced diameter bore 17 and a counterbore 18, there being a downwardly tapering shoulder 19 between the two bores. A tubular head 20 having a bore 21 and a threaded counterbore 22, is threaded at 23 into the upper end of the housing. Although the head 20 is capable of vertical adjustment, if for any reason such adjustment is found desirable, it will ordinarily be screwed fully down to seat on body shoulder 24. Fluid leakage from within the housing around the head is prevented by suitable means, such as a packing ring 25.

The tubular head 20 conveniently provides a mounting for a radially compressible rubber packer 26 preferably in the form of a continuous

annular sleeve normally having a substantially uniform diameter bore 27 with beveled surfaces at 28 and 29, see Fig. 3, an outer and upper cylindric surface 30, and a downwardly tapering or conical surface 31. The upper end of the packer sleeve is supported by the lower tubular portion of the head 20. One of the important features of the invention is an improved connection between the support and packer that will withstand, without damage to either the connection or packer, the various distortions to which the latter may be subjected under conditions of operation under high pressure. As illustrated in Fig. 2, the packer sleeve in its constricted condition, is deflected inwardly about the work, for example the drill pipe 32. Under extreme well pressures, the packer may be forced upwardly within space 33 between pipe 32 and the bore 21, a distance considerably above the position shown. The result is that the packer is subjected to severe shearing stress at the lower edge 21a of bore 21, as well as to an inward radial strain tending to shear the upper surface 28a of the packer from its mounting. This inward radial distortion of the upper end of the packer extends, though to a progressively lessening degree, to its outer periphery. Thus the radially inward deflection and distortion of the packer resulting from its being forced up into the space 33, is least within the outer portion indicated at 34.

The packer mounting, generally indicated at 35, comprises a ring 36 that preferably is removably attached to the tubular head 20 by suitable means, as for example by pins 37, see Fig. 5, inserted within bores 38 extending through the ring and intersecting the head 20. As will be apparent, these pins may be driven out of the bores to disconnect the ring 36. The packer 26 is connected to and suspended from the mounting 35 by a continuously annular fabric material 39, which may be formed in multiple ply or by a suitable number of separate fabric layers, embedded within the packer and extending downwardly and inwardly within the rubber at the outer portion 34. The upper and inwardly turned portion of the fabric is clamped between ring 36 and ring 40 attached to the former by screws 41. The top surface 28a of the packer bears against the bottom surfaces of ring 40 and head 20 which are provided with annular ridges, and into the spaces between which the rubber flows when the packer is subjected to upward compression. These ridged surfaces of the ring and head act to form an extremely strong bond with the packer for the reason that as the rubber is forced into the inter-ridge spaces, the air is expelled from the spaces, and thereafter the fluid pressure in the head tightly holds the rubber to the metal surfaces. An annular, double lipped packing 42 prevents any fluid that might leak outwardly between the lower end of head 20 and the packer, from escaping past ring 36. The packer sleeve is internally reenforced at its upper end by suitable flexible reenforcing material, preferably layers of fabric 43, embedded in the rubber and extending horizontally inwardly and then downwardly below the bottom of surface 33.

As will be understood from the foregoing, the fabric 39 connecting the packer with the mounting is advantageously positioned to withstand the most severe usage and distortion of the packer, by reason of its being embedded in the outer portion 34 of the rubber at which the least deflection and distortion of the packer occurs. Tear-

ing and stripping of the rubber from the packer, as might otherwise result from rotation of the drill pipe with the packer rubber forced upwardly in space 33, is effectively prevented by the reinforcing fabric 43, and the fact that the latter is extended inwardly and downwardly adjacent the packer bore where the wear and stresses on the rubber are the greatest. We have previously explained how at times the combination of radial contraction of the packer and well pressure applied thereto will force the rubber upwardly within space 33 and cause greater displacement or movement of the rubber at the inner surface of the packer support than toward the peripheral portion thereof. The feature of locating the fabric attachment 34 within the outer interior of the packer is of great importance in that the fabric thus is removed from the inner portion of the rubber subjected to greatest distortion and where the tendency of the rubber to become sheared from its support is greatest, with the result that the fabric is not subjected to bending and shearing strains that otherwise might be sufficient to rupture it and thereby sever the packer from its support. It will be understood that materials other than fabric may be utilized in the arrangement illustrated, to support and reinforce the packer, although fabric is preferred because of its inherent flexibility and rubber bonding qualities.

The packer contracting piston 45 has upper and lower portions 45a and 45b of differential diameters corresponding to the diameters of the housing bores 18 and 17, respectively, the piston having a sliding fit within the housing and carrying suitable packing rings 46 to prevent fluid leakage. The angularity of the intermediate tapered portion 47 of the piston is somewhat greater than the angularity of the housing shoulder 48, so as to provide an annular space at 49 between the piston and housing, for the introduction of pressure fluid for purposes later to be explained. In its lowermost position, see Fig. 3, the piston seats on annular surface 50, the angularity of which corresponds to the taper of the piston surface 47.

The contractor 45 has a bore 51 of substantially the same taper as surface 31 of the packer, so that as the contractor moves upwardly relative to the packer, it acts to constrict the latter radially inward against the work 32. The relative positions of the contractor 45 and packer 26 in constricted condition, are illustrated in Fig. 2, wherein the rubber is shown to be compressed against the pipe 32 with the upper bore surface 28, beveled to prevent tearing, of the packer forced inwardly at the bottom of space 33.

The lower depending portion of the tubular head 20 is spaced at 53 from the wall of the housing to provide an annular chamber containing a ring 54 that is attached to the contractor piston and forms with it, what may be termed the piston assembly. As illustrated in Fig. 5, ring 54 is detachably secured to the top of the contractor piston, by means of removable pins 55 inserted within open end bores 56 terminating in piston 45 and intersecting ring 54. The latter carries suitable packing means 57 sealing the piston against downward fluid leakage. The purpose of ring 54 primarily is to communicate to piston 45 the pressure of fluid introduced to chamber 53, as will later be explained. It will suffice to state at this point that as a result of fluid pressure applied to ring 54, the contractor 45 is moved downwardly from the posi-

tion of Fig. 2 to that of Fig. 3, to release the packer from the work. A vent passage 58 is formed in the upper portion of the contractor 45 for the purpose of releasing from space 59 below ring 54, any operating fluid that might leak past the piston into space 59 and otherwise tend to resist downward movement of the piston assembly. Vent passage 58 communicates at its lower end with chamber 49 and with space 59 by way of port 60, see Fig. 6, controlled by a spring 61 pressed check valve 61. The valve unseats to pass fluid from space 59 into chamber 49 as the piston assembly moves downward, and at other times is held in seated position by the spring 62 to prevent return flow of the pressure fluid from chamber 49.

Adjustable stop means, generally indicated at 63, is provided for the purpose of limiting the upward travel of the piston assembly, and also to limit the degree to which the packer is constricted about the work in the uppermost position of the piston, independently of the amount of fluid pressure being exerted upwardly against the piston to compress the packer. In one form the adjustable stop means comprises a plurality of circularly arranged set screws 64 extending through the head 20 and a packing retaining ring 65 into space 53. Individual packing rings 66 prevent leakage of the high pressure fluid around the set screws. Normally, screws 64 will be set to limit the upward travel of the piston assembly at a point to which packer 26 will be constricted about the work with sufficient tightness to prevent any considerable upward leakage of fluid, but at the same time to permit just enough fluid leakage through the packer to lubricate its engagement with the work. This type of adjustable piston stop is disclosed in the earlier filed application referred to above. The present invention constitutes an improvement in the stop means in that it provides means for the simultaneous adjustment of all the individual set screws 64, as by the adjustment of any one of them, thus obviating the necessity for adjusting each set screw, and assuring that the screws will be adjusted to exactly the same vertical positions.

Each of the set screws 64 carries a sprocket 68 meshing with a circularly continuous chain 69, see Fig. 4, contained within and tightened 50 against the base of an annular groove 70 formed within rings 71 and 72. These rings are secured together by screws 73 and are supported on the annular shoulder 74 of a ring 75 resting on sprockets 68 and through which the upper ends 55 of the set screws project. Rings 71 and 72 serve as a floating carrier for the chain 69, the rings in the lower head 11 extending loosely about the pipe 14 and similarly, in the upper head 10, about a nipple 76 threaded into counterbore 22 of member 20. As will be apparent, by adjusting any individual set screw 64, all the other set screws whose sprockets 68 are meshed with the chain 69, are correspondingly adjusted in the same direction and to the same degree.

The upper head 10 is constructed to operate automatically as a blow out preventer, and in this respect its structure differs in certain respects from the construction of the lower head 11. The packing contractor piston 45 in the upper head is made automatically responsive to sudden increases in the well pipe pressure so as to automatically constrict the packer about the drill pipe, by means of a second packer, generally indicated at 78, carried within the lower portion of 75 the piston 45. This lower packer 78 preferably

will be made to maintain a fairly tight fluid seal between the piston 45 and the drill pipe, although some leakage past the packer 78 may occur without disturbing its effectiveness as a blow out preventer, since the packer and constrictor assembly 5 will necessarily be actuated when a blow out occurs, because of the great volume of well fluid released under high pressure. Thus packer 78 serves primarily to provide sufficient seal or restriction about the work that will cause a more or less sudden increase of fluid pressure in the pipe 14 to raise the piston 45 and constrict the upper packer 26.

Packer 78 comprises a rubber sleeve 80 vulcanized to an outer cylindric tube 81 inserted within the piston counterbore 82, tube 81 having clearance at 801 from the bore wall and at 811 from the shoulder at the top of the counterbore so as to be freely rotatable together with the packer, within the piston. The packer is supported on a retaining ring 84 threaded into the lower end of bore 82 and held in place by set screw 841. The bottom of the packer extends outwardly below the lower end of tube 81 and is provided with an annular lip 802 adapted to be forced outwardly by fluid pressure into sealing engagement with the wall of bore 82. The packer 80 is moulded about a perforated reenforcing metal tube 85, the rubber filling the tube perforations 85a to effectively integrate the metal tube with the rubber body in such manner that the former will hold the rubber from "flowing" or gathering as the pipe collar 32a passes through. The rubber packer 80 has an inwardly projecting annular lip 86 engaging the outer surface of the pipe and having a downwardly inclined upper surface 87 and a lower substantially flat or slightly inclined surface 88.

It is desired to taper the top surface 87 of the packing lip in order to facilitate downward passage of the pipe collar through the packing against pressure in pipe 14. By virtue of its shape, lip 86 is reenforced against and made relatively resistant to upward deflection by fluid pressure or by the pipe collar, so as to effectively withstand any severe conditions of wear that might result from repeatedly pulling the collars through it as the pipe string is elevated. The packer lip however offers less resistance to downward movement of the pipe collars through it, since the lip will more readily deflect in a downward direction. Upon engagement by the collar, the lip is doubled upwardly or downwardly, in accordance with the direction of collar movement, into the spaces at 89 and 90 proportioned to afford ample clearance between the packing and collar to accommodate deflection of the lip.

The lower packing head 11 is provided below the piston 45 with a vertically movable pipe contacting means, generally indicated at 91, that operates as a part of a signalling system for indicating the upward passage of the pipe collars 32a past a predetermined point below the packer constricting piston, during withdrawal of the drill pipe from the well. The vertically displaceable means indicated at 91 is to be regarded merely as typical of various suitable devices that are upwardly displaceable upon engagement by the pipe collar, and capable of actuating the later described parts of the signalling system. In its preferred form, the device 91 comprises a cylindric ring 92 slidably engaging bores 94 and 95 of the head and coupling 15, respectively, and having its outer surface channeled at 93 to reduce frictional contact with the bore walls. Normally, and in its lowermost position, ring 92 seats on an 75

annular shoulder 96, the ring assembly being shown elevated from its seat in Fig. 3 merely for purposes of illustration and description. Clamped between the upper portion 92a of the ring and a retaining ring 97 threaded into its lower end, is a perforated tube 98 carrying a plurality of circularly spaced rubber lugs 99 molded integrally with the tube and projecting inwardly to an extent that they will be engaged by the pipe collar 32a as the drill string is elevated. Preferably, in order to prevent the ring from becoming untimely raised as a result of contact between the rubber lugs and the pipe between couplings, the lugs will have the maximum clearance from the outside surface of the pipe 32 (assuming the work in Fig. 3 to consist of a circular drill pipe), that can be maintained and yet have the lugs engaged by the pipe collar with sufficient tightness to raise the ring. Rings 92 and 97 may contain circularly spaced openings 100 and 101 to provide space, in addition to the spaces between the rubber lugs, for fluid to pass through the ring without the fluid flow being restricted to the extent that the ring assembly will be elevated by fluid pressure alone. In case the pipe is rotating with the collar in engagement with the lugs, tube 98 and the lugs, or the entire ring assembly, may rotate within the housing.

Upward movement of ring 92 past a predetermined point operates a suitable signal actuating device, typically of the character indicated generally at 102, and shown in detail in Figs. 7 and 8. The device 102 comprises a laterally displaceable tubular piston 103 including an enlarged diameter head portion 104 contained within the housing bore 105, and a tubular stem portion 106 movable longitudinally within the bore of fitting 107 threaded into the housing counterbore 108. The piston head 104 contains a check valve 109 which is normally seated by coil spring 110 to prevent leakage through opening 111 of the pressure communicating fluid contained in the signalling system. The piston normally is thrust outwardly to project the rounded end of the head 104 into the housing bore 94 by coil spring 112, the inward position of the piston being determined by engagement of the enlarged end 106a of the head with shoulder 114 at the end of the fitting bore 115.

50 The lateral or vertical pressure acting against the piston 103 is balanced by communicating the well pressure via space 103c and opening 103b, to annular grooves 103a in the piston, the groove at the left also connecting opening 103b with chamber 103d.

55 The fitting 107 is connected with a suitable pressure indicator or gage 116, see Fig. 1, by pipe 117, and the pipe, fitting and piston 103, all are filled with a suitable pressure communicating fluid, for example a rather heavy but flowable oil, so that outward displacement of the piston from the position of Fig. 7 to that of Fig. 8, will develop fluid pressure in line 117 that is indicated by the gage 116. The system may be charged with the oil in any suitable manner, as by introducing the oil through a fitting 118 below the gage, and holding the check valve 109 open with the piston positioned as in Fig. 7, until oil discharges through opening 111, indicating that all the passages between the valve and gage are filled with oil. Preferably, line 117 will be charged with fluid at a pressure greater than the casing fluid pressure, to insure against the piston being forced outwardly 70 by the well pressure. Should the fluid pressure

in the signalling system tend to drop below well pressure, check valve 109 will open to balance the pressures. Figs. 7 and 8 indicate the two positions of the indicator piston 103 before and after engagement by the outwardly inclined surface 92b of the ring 92, as the latter is elevated by the engagement of collar 32a with the rubber lugs 99. As the ring moves up, surface 92b cams the piston 103 to the position of Fig. 8, developing a pressure in line 117 that is indicated on the gage 116. Ring 92 is limited in its upward position of Fig. 8 by engagement with suitable stop means, for example circularly spaced screws S projecting into the housing bore 24 at a level permitting cam surface 92b to travel upward while in engagement with the piston, a distance sufficient to cause the piston to communicate a pressure impulse, but limiting the upward travel of the ring assembly so that after the pipe collar has passed through, the piston still 15 will engage the cam surface. Thereupon, the ring assembly may drop by gravity to its lower position.

55 Referring now to Fig. 1, the upper and lower packing heads are interconnected by tie bolts B extending through ring 75 of the lower head and threaded at their upper ends into flange 15b of the upper coupling 15, and at their lower ends into the top portion of tubular member 20 in the lower packing head. The packer contracting pistons in the heads 10 and 11 are operated by pressure fluid that may be derived from any suitable source via line 119, or from the well casing 12 through line 120. The pressure fluid is supplied to the piston chambers in the two heads via line 121 which is communicable, under control of a four way valve 122, with chambers 53 and 49 in the upper head 10 via pipes 123 and 124, respectively, and with the corresponding chambers in the lower head 11 by way of lines 125 and 126, under control of four way valve 127. As the contracter pistons are moved vertically, fluid from one or the other of chambers 49 and 53, depending upon the direction of piston movement, is exhausted 40 through lines 128 and 129.

50 Referring to Fig. 2, it will be noted that the piston assembly, including piston 45 and ring 54, provides an upwardly facing pressure area, the top surface of ring 54 exposed to chamber 53, and two downwardly facing pressure areas, the tapered surface 41 of piston 45, and the lower end of this piston including the area of packer 78 between the bore of the retaining ring 84 and the outside of pipe 32. These pressure areas of the piston assembly may be conveniently designated in the order named, as P_1 , P_2 and P_3 . As illustrated, the combined areas of P_2 and P_3 is greater than the area P_1 , but P_1 is greater than either P_2 or P_3 , although it is only of importance that P_1 be greater than P_3 .

55 Advantage is taken of the differential pressure areas of the piston assembly as a means whereby the packer 26 may be released from the work, while at the same time releasing movement of the contracter is resisted by the fluid pressure within the casing 12 acting against pressure area P_3 of the piston. Referring to Fig. 1, assuming line 121 to be in communication with line 120 connecting with the casing, by reversing the position of valve 122 to connect the discharge pipe 128 with space 49 via line 124, the well pressure is applied through line 123 and chamber 53 against the upper pressure area P_1 of the piston assembly. As stated before, the area P_1 70

is greater than P_3 , and with the pressure exhausted from space 49, the unbalanced pressure on areas P_1 and P_3 results in downward movement of the contractor and release of the packer 26 from the work.

As will be understood, only a single packing head may be used to maintain a seal about the work and to serve as a blow out preventer, without necessitating the use of the illustrated dual tandem arrangement that has the added utility of enabling a seal to be maintained while lowering or removing the drill pipe. To illustrate the operation of a single packing head, for example the upper head 10, the packer in the lower head 15 may be assumed to be released from the drill pipe and valve 130, Fig. 1, closed to render the lower head inoperative. To illustrate the operation of the upper head when the well starts to flow, as for example during drilling or at any 20 other time when the packer 26 normally is open, assume the parts to be in the positions of Fig. 1 with valve 131 closed and valve 132 opened, the pipe 119 to be connected with a source of pressure fluid, for example with the circulating fluid 25 pumps, not shown. Valve 122 is thrown to the position illustrated to communicate the pressure fluid to chamber 49 and to relieve pressure from chamber 53 above the piston. With the packer in this position, the pipe 32 may be rotated and 30 moved back and forth between the collars during the operation of conditioning the circulating mud in the well to the point where the flow is under control. Then the packer may be released by reversing valve 122 to communicate the fluid pressure to chamber 53 and exhaust the pressure from chamber 49. When the 35 packer contractor is independently controlled and operated by fluid pressure from line 119 as just explained, the lower packer 78 need not necessarily be used, as the operator has full control in the event of sudden development of pressure in the well.

Fig. 3 illustrates the adaptability of the piston actuated packer to seal about work of polygonal cross section, for example an octagonal drive stem or kelly 32b. The packer also is capable of sealing about drive stems of other cross sectional shapes, the octagonal form being shown as typical. The fact that our improved packing head can maintain a substantially fluid-tight seal about a polygonal cross section drive stem rotating within the packer, is of great advantage and importance in that the necessity for the usual relatively complicated and expensive devices employed to seal off around the drive stem, is obviated in favor of a single and relatively simple packer sleeve capable of sealing around any section of the drill string, regardless of its cross sectional shape. The ability of the packer to seal about the drive stem and to withstand the continuous flexure and deformation resulting from the rotation of the drive stem in the normally circular and contracted packer bore, is due to the provision of means independent of, or in addition to, the contractive effect of well fluid pressure acting against the packer, for positively contracting the packer into engagement with the flat surfaces of the drive stem, and means for allowing a restricted leakage of fluid through the packer to lubricate its engagement with the drive stem surfaces. Lubrication is essential in order for the rubber to withstand the wear and deflection resulting from the polygonal body rotating within it.

As will be understood from the foregoing, to set

the packer about the drive stem, pressure fluid is introduced to chamber 49, causing the piston to raise and constrict the packer into engagement with the flat surfaces of the drive stem as shown in Fig. 2a. Movement of the piston in a packer 5 contracting direction, and therefore the extent of packer contraction, are limited by proper adjustment of stop screws 64, to permit a slight upward leakage of well fluid through the packer for the purpose, as stated, of lubricating its contact with the drive stem. Tests have demonstrated that under these conditions, the packer is capable of maintaining, except for the slight leakage, a seal about the drive stem over long periods of operation.

To understand the operation of the two packing heads 10 and 11, assume that the drill pipe 32 is being pulled from the well, and that the packer 26 in the upper head is closed about the pipe as shown in Fig. 2, with the packer in the lower head 15 in the released position of Fig. 3. Assuming the well to be under pressure, valve 132 may be closed and valve 131 opened to supply pressure fluid to line 121 from the casing 12. Generally speaking, the two packing heads are operated to 20 pass successive pipe couplings 32a without loosening the fluid seal around the pipe, by keeping the upper head 10 closed until the coupling passes above the packer 26 in the lower head 11, after which the latter is closed and the packer in the 25 upper head opened, to permit the collar to pass on through. The described signalling system is used to control the operation of the heads, since it indicates the position of the pipe collar with 30 relation to the lower packer and enables the operator to determine when the coupling has passed through the lower packer, so that the latter may be closed and the upper packer opened.

Thus, as the collar 32a engages and elevates the ring assembly 91, the signalling system indicates the position of the collar by pressure increase on the gage 116 resulting from outward displacement of the piston 103, all in the manner previously explained. By observing the movement of drill pipe extending above the upper 40 head 10 the operator is able to visually gauge the distance that the coupling 32a must travel to move up through the packer in the lower head. At that point, valves 122 and 127 are reversed, causing the packer in the lower head to close 50 about the pipe below the coupling, and the packer in the upper head to open for the purpose of passing the coupling.

As will be understood without the necessity of further and repetitious explanation, the upper 55 and lower packing heads are operated in a reversed sequence while drill pipe is being lowered into the well. As the pipe goes into the well, the position of the coupling with relation to the packer in the upper head, is gauged by reference 60 to the top portion of the housing, the described signalling system being used only during withdrawal of the pipe.

Fig. 9 shows a variational form of packing head 65 similar in general respects to the type illustrated in Fig. 3, but differing principally in the particular form of piston stop adjusting means, the arrangement, relative to the packer, of the signal actuating device, and the construction of the main packer. Parts that are the same as those 70 previously described are given the same reference characters. In this variant form, the vertically movable stop pins 135, slidable longitudinally within bores 136 in the head 20', are adjustable by means of a rotatable ring 137 provided with 75

sockets 138 to receive a manipulating tool, and threaded at 139 on an upper tubular extension 140 of the housing screwed into bore 141 of member 20. The housing extension 140 has an interior work centering flange 142 presenting a downwardly and inwardly inclined surface 143, and a bottom shoulder 144 that serves as a stop for the signal actuating ring assembly 145. The upper ends of pins 135 are received within an annular groove 146 in the bottom face of ring 137.

In the drawings, the stop pins 135 are shown to be maintained in raised position by frictional engagement with the individual packers 147. As will be apparent, by rotating ring 137, the stop pins may be maintained in different but corresponding positions of adjustment relative to the packer and its actuating piston.

In Fig. 9, the plunger actuating ring assembly 145 is movable vertically within bore 148 between shoulder 144 and shoulder 149 of the head 20'. The construction of the ring assembly is generally similar to the previously described form, excepting that the packing 150 is more nearly the internal diameter of the outer sleeve 151, and the rubber lugs 152 have square cut under-shoulders 153 that are engaged by the couplings as the pipe string is elevated.

The piston, generally indicated at 154, differs from the form shown in Figs. 7 and 8, principally in that the pressure of fluid in line 117, alone is utilized to maintain the plunger in its projected position, the spring being eliminated. The rounded plunger head 155 contains a bore 156 through which fluid pressure is communicated from within the housing to chamber 157; the sides of the piston being flattened at 158 to establish open communication between the chamber and transverse bores 159 connecting with bore 156. The piston is thrust into the housing bore to a limiting position determined by the engagement of the piston carried lugs 160 with bushing 161, by fluid pressure applied at the outer end of rod 162 sealed around by suitable packing 163. Upward movement of ring 151 by the pipe collar to position of engagement with shoulder 144 thrusts the piston outwardly, developing an indicated pressure in line 117. After the collar passes through the rubber lugs, the fluid pressure against piston rod 162 returns the piston to the position illustrated, causing the rounded piston nose to cam ring 151 downwardly.

In Fig. 9 we have shown, in addition to the check valve 61 past which fluid is released from chamber 59 through passage 58, a second pressure relief passage formed by a bore 164 in portion 54 of the piston, and controlled by downwardly seating spring pressed check valve 165. This second pressure relief passage and valve are provided as a means of permitting the piston to move downwardly to its lowermost position, in the event passage 58 should for any reason become clogged against fluid escape therethrough. Assuming passage 58 to be closed, as the piston moves downwardly, check valve 165 will unseat and pass fluid from space 59 to chamber 53 at the point at which the pressure in 59 starts to exceed the pressure in 53. The piston will then continue its downward travel, despite the communication between the two chambers, by reason of the larger pressure area P_1 exposed to the upper chamber.

The main packer 166 has a substantially cylindrical bore 167, and an annular lip 168 projecting inwardly from the bore wall. Broadly speaking

lip 168 may have any suitable shape, although preferably it is so formed that while in engagement with the work, as it normally is, the lip is more resistant to upward deflection than to downward deflection. Typically, the lip may be formed with an upper, downwardly and inwardly inclined surface 169, and a lower surface 170 of comparatively less angularity in a downward and outward direction, so as to render the lip less resistant to downward deflection. By reason of its under surface being cavitated as at 171, the lip is less resistant to downward deflection because of the removal at 171 of rubber that would otherwise reinforce the lip against downward deflection. Comparatively, the lip is more resistant to upward deflection by reason of the reinforcement afforded by the rubber at 172. The outer surface of the packer has an annular cavity 173 substantially opposite the lip 168 to provide a space into which the rubber may flow or expand when the packer is contracted.

Lip 168 is itself capable of providing a fluid-tight seal about the pipe 32, without contracting the packer from the position shown, at such times as the casing pressure is comparatively low, for example not in excess of 300 pounds per square inch. The lip is maintained in sealing engagement with the surface of the pipe by the upwardly applied fluid pressure, and by reason of its shape characteristics, the lip is sufficiently resistant to upward deflection that it will hold the pressure. As the pipe contacting surface of the lip becomes worn, the piston may be raised sufficiently to compensate for such wear by radially compressing the packer and lip, stops 135 being adjusted, if desired, to limit the piston travel. By virtue of its reinforced characteristics, the lip will withstand repeated passage of pipe collars upwardly through it, and, after the passage of each collar, the lip will return to its illustrated position of sealing engagement with the pipe. As the pipe string is being lowered through the packer, the lip will deflect downwardly to pass the collars, without becoming appreciably worn.

In the event the well develops comparatively high pressures that the lip 168 will not hold, the packer may be bodily contracted about the pipe to bring the packer bore 167 into sealing engagement therewith. Upon radial contraction of the packer, the lip, relatively, will be forced in the body of the packer and the rubber will expand into cavity 173 to compensate for the lip displacement. It is important to observe that even though the lip should be severely worn, even to the point of severance from the body of the packer, the latter still may be contracted about the pipe to maintain a fluid-tight seal.

We claim:

1. In a packing head for well pipe, a tubular housing adapted to take work through its bore, the walls of the housing forming a closed space, radially contractible packing in the housing and about the work, a member movable to contract the packing, a plurality of movable stops extending within said space and engageable by said member in its packing contracting movement, and means for adjustably moving said stops simultaneously relative to the housing and packing and said contracting member.
2. In a packing head for well pipe, a tubular housing adapted to take work through its bore, the walls of the housing forming a closed space, radially contractible packing in the housing and about the work, a member movable to contract the packing, a plurality of movable stops ex-

- tending through the wall of the housing into said space and engageable by said member in its packing contracting movement, and an adjustable member movable relative to said housing and maintaining said stops in different but corresponding positions of adjustment relative to the packing and said contracting means.
3. In a packing head for well pipe, a tubular housing adapted to take work through its bore, said housing containing a closed space, radially contractible packing in the housing and about the work, a fluid pressure actuated piston for contracting the packing, means for introducing fluid to said space to actuate the piston, a plurality of movable stops extending within said space and engageable by said piston in its packing contracting movement, and adjustable means movable relative to said housing and operable to maintain said stops in different but corresponding positions of adjustment relative to the packing and said contracting member.
4. In a packing head for well pipe, a tubular housing adapted to take work through its bore, radially contractible packing in the housing and about the work, a fluid pressure actuated piston for contracting the packing, a plurality of movable stops engageable by said piston in its packing contracting movement, and an annular and rotatably adjustable means coacting with said stops to position them in different but corresponding positions of adjustment relative to said packing and contracting means.
5. In a packing head applied to a well pipe, a tubular housing adapted to take an elongated member through its bore, a radially contractible packer in the housing and about the work, a packer support, a packer contracting piston movable upwardly within the housing by fluid pressure to constrict the packer about said member, said piston and support enclosing a chamber about the packer, means forming a fluid vent passage leading from said chamber, a check valve preventing return flow of fluid through said passage into the chamber, and means for moving said piston vertically by fluid pressure.
6. In a packing head for well pipe, a housing, a tubular packer within the housing and adapted to take work through its bore, a portion of the packer bore wall normally being spaced about the work, an annular lip projecting inwardly from said portion of the bore wall and engaging said work to seal around it, and a fluid pressure actuated tubular piston surrounding said packer and operating to press said normally spaced portion of the packer bore wall into engagement with said work, the outside of said packer within the piston being recessed to accommodate outward displacement of the packer material as the packer is contracted about the work.
7. In a packing head applied to a well casing, a tubular housing adapted to take collared pipe through its bore, radially contractible packing in the housing and about the pipe, means for contracting the packing about the pipe, means actuated by fluid pressure for indicating vertical movement of the pipe collar to a predetermined position relative to the packer, and an annular pipe surrounding member displaceable vertically by engagement with a pipe collar for actuating the last mentioned means.
8. In a packing head applied to a well casing, a tubular housing adapted to take collared pipe through its bore, radially contractible packing in the housing and about the pipe, means for contracting the packing about the pipe, a member movable laterally by virtue of vertical movement of the pipe collar, fluid pressure actuated means indicating lateral movement of said member, and an annular pipe surrounding member displaceable vertically by engagement with a pipe collar for actuating the last mentioned means.
9. In a packing head applied to a well casing, a tubular housing adapted to take collared pipe through its bore, radially contractible packing in the housing and about the pipe, means for contracting the packing about the pipe, an indicator, a line charged with fluid under pressure at least as great as the well casing pressure, and means actuated by virtue of pipe collar movement for communicating pressure to the fluid in said line, the last mentioned means including an annular pipe surrounding member displaceable vertically by engagement with a pipe collar.
10. In a packing head applied to a well casing, a tubular housing adapted to take collared pipe through its bore, radially contractible packing in the housing and about the pipe, means for contracting the packing about the pipe, a vertically movable annular member surrounding the pipe and adapted to pass the pipe collar, said member being upwardly displaceable when engaged by the pipe collar, and means indicating upward movement of said member.
11. In a packing head applied to a well casing, a tubular housing adapted to take collared pipe through its bore, radially contractible packing in the housing and about the pipe, means for contracting the packing about the pipe, a vertically movable member surrounding the pipe, and centering the pipe relative to said packing, said member being adapted to pass the pipe collar and being upwardly displaceable when engaged by the pipe collar, and means indicating upward movement of said member.
12. In a packing head applied to a well casing, a tubular housing adapted to take collared pipe through its bore, radially contractible packing in the housing and about the pipe, means for contracting the packing about the pipe, an annular member surrounding the pipe and adapted to pass the pipe collar, yieldable means carried by said member and engageable by a pipe collar, said member being upwardly displaceable upon engagement of said yielding means by the pipe collar, and means indicating upward movement of said member.
13. A packing head for well pipe comprising a tubular body adapted to take work through its bore, a tubular packer, a support for one end of the packer, a packer contracting piston movable toward said support to axially compress and radially contract the packer about the work, the inner portion of the packer adjacent said support being displaceable, when the packer is radially contracted, into a space between said support and the work, and fabric embedded in the packer and having a projecting end portion attached to said support, said fabric being spaced substantially further from the packer bore than from the outside of the packer so as to permit said displacement of the inner portion of the packer adjacent the support without subjecting said end portion of the fabric to rupture by bending and shearing strains.
14. A packing head for well pipe comprising a tubular body adapted to take work through its bore, a continuously annular packer, a support for one end of the packer, a packer contracting piston movable toward said support to axially compress and radially contract the packer about the work.

the work, the inner portion of the packer adjacent said support being displaceable, when the packer is radially contracted, into a space between said support and the work and continuously annular fabric embedded in the packer and having a projecting end portion attached to said support, said fabric being spaced substantially further from the packer bore than from the outside of the packer so as to permit said displacement of the inner portion of the packer adjacent the support without subjecting said end portion of the fabric to rupture by bending and shearing strains.

15. A packing head for well pipe comprising a tubular body adapted to take work through its bore, a continuously annular packer having a longitudinally tapered surface, a support for one end of the packer, a tapered bore packer contracting piston movable toward said support to axially compress and radially contract the packer about the work, the inner portion of the packer adjacent said support being displaceable, when the packer is radially contracted, into a space between said support and the work, and continuously annular fabric embedded in the packer and having a projecting end portion attached to said support, said fabric extending longitudinally and inwardly within the packer from its point of attachment to the support and being spaced substantially further from the packer bore than from the outside of the packer so as to permit said displacement of the inner portion of the packer adjacent the support without subjecting said end portion of the fabric to rupture by bending and shearing strains.

35. 16. A packing head for well pipe comprising a tubular body adapted to take work through its bore, a continuously annular packer, a support for one end of the packer, a packer contracting piston movable toward said support to axially compress and radially contract the packer about

the work, the inner portion of the packer adjacent said support being displaceable, when the packer is radially contracted, into a space between said support and the work, and continuously annular fabric embedded in the packer and having a projecting end portion, an annular member clamping said projecting end portion of the fabric to said support, said fabric being spaced substantially further from the packer bore than from the outside of the packer so as to permit said displacement of the inner portion of the packer adjacent the support without subjecting said end portion of the fabric to rupture by bending and shearing strains.

17. A packing head for well pipe comprising a tubular body adapted to take work through its bore, a continuously annular packer having a longitudinally tapered surface, a support for one end of the packer, a tapered bore packer contracting piston movable toward said support to axially compress and radially contract the packer about the work, the inner portion of the packer adjacent said support being displaceable, when the packer is radially contracted, into a space between said support and the work, and continuously annular fabric embedded in the packer and having a projecting end portion, an annular member against which the end of the packer bears, for clamping said projecting end portion of the fabric to said support, said fabric extending longitudinally and inwardly within the packer from its point of attachment to the support and being spaced substantially further from the packer bore than from the outside of the packer so as to permit said displacement of the inner portion of the packer adjacent the support without subjecting said end portion of the fabric to rupture by bending and shearing strains.
